(57) **CLAIM**

The ornamental design for a mobile device stand, as shown and described.

DESCRIPTION

FIG. 1 is a perspective view mobile device stand, showing my new design;

FIG. 2 is a side elevation view thereof;

FIG. 3 is a top elevation view thereof;

FIG. 4 is a bottom elevation view thereof;

FIG. 5 is a front elevation view thereof; and,

FIG. 6 is a rear elevation view thereof.

The broken lines shown in the drawings illustrate portions of the mobile device stand that form no part of the claimed design.
